UNITED STATES PATENT OFFICE.

HELENE HOFFA GOLDMAN, OF PITTSBURGH, PENNSYLVANIA.

DESIGN FOR A TEETHING-RING.

48,785.

Specification for Design.

Patented Mar. 28, 1916.

Application filed October 13, 1914. Serial No. 866,553. Term of patent 7 years.

To all whom it may concern:

Be it known that I, HELENE HOFFA GOLDMAN, a citizen of the United States, residing at Pittsburgh, in the county of Allegheny and State of Pennsylvania, have invented a new, original, and ornamental Design for Teething-Rings, of which the following is a specification, reference being had to the accompanying drawing, forming part thereof.

The figure is a plan view of the teething ring, showing my new design.

I claim:

The ornamental design for a teething ring, as shown.

HELENE HOFFA GOLDMAN.

Witnesses:

GEO. S. WILSON,
JOSEPH N. DALFONZO.
